UNITED STATES PATENT OFFICE

ARTUR SCHALKAU, OF BERLIN-CHARLOTTENBURG, GERMANY, ASSIGNOR TO SIEMENS-SCHUCKERTWERKE GESELLSCHAFT MIT BESCHRANKTER HAFTUNG, OF SIEMENS-STADT, NEAR BERLIN, GERMANY, A CORPORATION OF GERMANY.

HOLLOW ROPE CONDUCTOR FOR OVERHEAD TRANSMISSION LINES.

Application filed June 23, 1928, Serial No. 117,889, and in Germany February 4, 1928.

My invention relates to hollow rope conductors for overhead transmission lines.

In hollow or tubular rope conductors which consist of two or more layers of line wires stranded over a supporting member or element, a considerable combined tension and compression stress is developed during the laying as well as in service, inasmuch as the longitudinal pressure caused by the weight of the rope forces the wires towards the interior and thus against the supporting element. At the places of the inner layer of wires where the wires rest with comparatively small surfaces upon the support, a notching action is thus set up, which when the rope is repeatedly bent frequently leads to a rupture of the rope at those places.

The object of my invention is to eliminate this drawback. I attain this end in view by making the cross-sectional area of the wires of the inner layer larger than the cross-sectional area of the wires of the outer layer or layers. In the inner layer of wires of large cross-section an arch is provided in this manner which supports itself and to which the supporting element only serves as idle or false framing. The wires of the inner layer are not forced against the supporting member by the longitudinal pull but take up the pressure mutually in the manner of the stones in an arch so that any notching of the wires by the supporting element is entirely eliminated. Preferably the wires of the inner layer are given at least double the cross-section of the wires in the outer layer.

In order to impart to the wires a good mutual supporting capacity, the wires of the inner layer are according to my invention made of greater thickness in a radial direction than the wires of the outer layer. Preferably the ratio of the thickness of the wires of the inner layer to that of the outer layer is made at least 1.5:1. An inner layer of wires thus designed is entirely self-supporting so that the rope completely maintains its round form essential for the avoidance of corona effects and does not become distorted like the hitherto employed

hollow rope constructions of equal wire thickness in the inner and outer layer, so that the shape of the supporting member becomes clearly visible upon the surface of the rope.

In the drawing affixed hereto a cross-section through the improved hollow or tubular conductor is shown.

Referring to the single figure of the drawing, 1 is the twisted strip serving as supporting member, 2 the wires of the inner layer which possess double the cross-sectional area as the wires 3 of the outer layer and the radial thickness of which amounts to 1.5 times the thickness of the outer wires. For the purpose of ensuring a good mutual support all the wires are designed as sectorial elements of a cylinder. It will be understood that more than two layers of wires may be employed.

Various modifications and changes may be made without departing from the spirit and the scope of my invention, and I desire, therefore, that only such limitations shall be placed thereon as are imposed by the prior art.

I claim as my invention.—

1. A hollow rope conductor for electric overhead transmission lines, comprising an internal shape defining member and a plurality of layers of sector-shaped line wires stranded over said internal member, the cross-sectional area of the wires in the inner layer being larger than the cross-sectional area of the wires in the outer layers, to permit the inner layer to form a strong arch-like support for the outer layers.

2. A hollow rope conductor for electric overhead transmission lines, comprising an internal shape defining member and a plurality of layers of sector-shaped line wires stranded over said internal member, the cross-sectional area of the wires in the inner layer being at least double the size of the cross-sectional area of the wires in the outer layer, to permit the inner layer to form a strong arch-like support for the outer layers.

3. A hollow rope conductor for electric overhead transmission lines, comprising an

internal shape-defining member and a plurality of layers of sector-shaped line wires stranded over said internal member, the cross-sectional area of the wires in the inner layer being at least double the size of the cross-sectional area of the wires in the outer layer and the thickness of the wires of the inner layer in a radial direction being greater than that of the outer layers, to permit the inner layer to form a strong arch-like support for the outer layers.

4. A hollow rope conductor for electric overhead transmission lines, comprising an internal shape-defining member and a plurality

of layers of sector-shaped line wires stranded over said internal member, the cross-sectional area of the wires in the inner layer being at least double the size of the cross-sectional area of the wires in the outer layer and the thickness of the wires of the inner layer to that of the wires of the outer layers being at least in the ratio of 1.5:1, to permit the inner layer to form a strong arch-like support for the outer layers.

In testimony whereof I affix my signature.

ARTUR SCHALKAU.
